WELL SCREEN

George W. Darst, San Jose, Calif.

Application November 24, 1936, Serial No. 112,521

1 Claim. (Cl. 166—5)

The present invention relates particularly to that type of screens used in deep well centrifugal pump installations, and for drainage purposes.

In the manufacture of well screens, where both

5 economy and efficiency are highly important factors, it has been somewhat common practice to build the screen of two thicknesses of sheet metal. This construction not only provides an extremely low-priced screen, but also one that is strong and 10 difficult to deform. In making this screen several different methods of perforating have been followed, chief of which are the following.

In one method of perforating, both the inner and outer tubes are perforated and then assembled with the perforations registering. One 15 of the principal objections to this method is that while the perforations may register perfectly when the two tubes are assembled, the rough handling of installation may move one tube relative to the 20 other in such a manner as to partially or even wholly offset the perforations, and consequently destroy or limit the efficiency of the screen.

In another method the perforations in the outer tube are made by punching outwardly with a 25 chisel thereby forming a slotted boss on the outside which interferes with the positioning of the screen. Furthermore, by this method pockets are formed between the outer slits and the inner tube, and these pockets are prone to fill with sand and 30 close off the flow of water.

It is, therefore, the object of my invention to provide a well screen of the type indicated that will not only be economical to manufacture, rigid, 35 strong, and highly efficient in its practical application, but also one that will not pack and close with sand, wherein the flow of water can not be shut off through displacement of one tube relative to the other, and wherein the screen will 40 present a smooth exterior surface with obvious advantageous results.

Other objects and advantages will appear in the following description and in the accompanying drawing, in which;

Figure 1 is a side elevation of a portion of a well 45 screen embodying my invention.

Figure 2 is an enlarged section on line 2—2 of Figure 1.

Referring now more particularly to the drawing, I show at 1 and 2 the inner and outer tubes of the screen, one fitting snugly within the other as clearly shown in Figure 2.

In the outer tube 2 are punched any required 5 number or arrangement of holes as indicated at 3, these holes being clean cut to leave the tube smooth on both the interior and exterior surface.

In the inner tube 1 are punched slots as 4. Each 10 slot 4 is disposed longitudinally of the tube and punched outwardly from the interior of the tube in such a manner, as with a chisel, to form lips 5 lying within the confines of the hole 3, and not projecting beyond the general outer surface of the outer tube. In forming the cuts 4 in this 15 manner inner pockets as 6 are formed, these pockets having the advantages hereinafter set forth.

A screen constructed in the manner described 20 cannot be rendered useless, or even partially so, by shifting of one tube relative to the other because the outwardly projecting lips 5 effectually prevent such movement, and the screen may be readily adjusted in a well because of its smooth 25 exterior surface.

In this form of screen there are no protuberances or bulges on the exterior against which sand 30 can lodge and build up, but rather the movement of both water and sand is rendered smooth and easy. This is due largely to the inwardly diverging 35 walls of the lips 5 forming the flaring pockets 6, whereby any material passing through the slots 4 passes away quickly and easily.

It is to be understood, of course, that while I 40 have shown the preferred form of my invention various changes may be made without departing 45 from the spirit of the invention.

I claim:

A well screen comprising, a tubular member having slots disposed longitudinally thereof and 40 punched outwardly from its inner side to form bosses on its outer surface, and a second tubular member overlying and encompassing the first member and having orifices formed therein encompassing said bosses. 45

GEORGE W. DARST.
